UNITED STATES PATENT OFFICE

CHARLES H. BORST, OF CUYAHOGA FALLS, OHIO

HOT WATER BOTTLE

Application filed February 8, 1930. Serial No. 426,956.

This invention relates to hot water bottles or similar containers, the primary object of the invention being to provide novel means whereby the bottle, which is constructed 5 preferably of elastic material, will retain its original contour when in use.

Another object of the invention is to provide means disposed within the water bottle and secured to the sides thereof to insure 10 against lateral elongation or stretching of the rubber, by the stays.

A further object of the invention is the provision of a device of this character which will reinforce the sides of the water bottle 15 to prevent spreading of the water bottle.

With the foregoing and other objects in view, which will appear as the description proceeds, the invention resides in the combination and arrangement of parts and in 20 the details of construction hereinafter described and claimed, it being understood that changes in the precise embodiment of the invention herein disclosed, may be made within the scope of what is claimed, without 25 departing from the spirit of the invention.

Referring to the drawings:

Figure 1 is a view illustrating a water bottle constructed in accordance with the invention, a portion of the side being broken 30 away to illustrate the interior construction of the bottle.

Figure 2 is a sectional view taken on line 2—2 of Figure 1.

Figure 3 is a sectional view taken on line 35 3—3 of Figure 1.

Figure 4 is a fragmental sectional view through a modified form of water bottle.

Figure 5 is a fragmental sectional view taken at right angles to Figure 4.

40 Referring to the drawings in detail, the body portion of the water bottle is indicated generally by the reference character 5, the same being constructed preferably of rubber and provided with a filling neck 6 and 45 stopper, not shown.

In the construction of the body portion of the bottle, reinforcing ribs 7 are provided, the ribs extending transversely of the body portion and arranged in parallel 50 spaced relation with each other. The refer-

ence character 10 designates strips of non-stretchable rubberized fabric cut in widths to fit between the reinforcing ribs 7, as clearly shown by Figure 2 of the drawings, where the strips 10 are cemented and vulcanized 55 in position, in the final curing of the bottle.

These strips 10 at opposite sides of the body portion of the bottle, are connected by cord stays 12, which stays have their ends passed through the fabric strips and secured 60 to the strips, the ends of the cords extending laterally, as clearly shown by Figure 1 of the drawings.

The cords of which the stays are constructed, are encased in tubular housings 11 65 which are connected to the strips of rubberized fabric, before the strips of rubberized fabric are positioned between the walls of the bottle.

In the form of the invention, as shown 70 by Figures 4 and 5 of the drawings, the stays which are indicated by the reference character 13, are formed preferably of lengths of fabric material, secured to the inner surfaces of the body portion as by vulcanizing 75 or cementing. The stays 13 may be arranged in any desired manner within the body portion, without departing from the spirit of the invention.

From the foregoing it will be obvious 80 that due to the construction shown and described, a water bottle is provided wherein the sides thereof will be held in predetermined spaced relation with each other at all times, eliminating any possibility of the 85 water contained in the body portion, bulging the body portion while in use.

A water bottle of this character may be held in a certain position on the body of the user without danger of the water in the bottle flowing to one end of the bottle and over-balancing the bottle to cause it to slide from the body of the user. 90

I claim:

1. A hot water bottle comprising a body portion formed of flexible material, stays embodying cords embedded in non-elastic material and secured to the sides of the body portion, and said stays being arranged in spaced relation with each other through- 100

out the length of the body portion to hold the sides of the body portion against movement beyond a predetermined point.

2. A hot water bottle comprising a body portion, pairs of spaced ribs formed on the inner sides of the body portion, strips of non-elastic material secured between the pairs of ribs, and non-elastic stays connected with the strips to hold the strips against movement away from each other.

3. A hot water bottle comprising a body portion formed of flexible material, pairs of spaced ribs formed on the inner surface of the body portion and disposed transversely of the body portion, strips of non-stretchable material secured between the ribs of each pair, non-stretchable stays secured to the strips and arranged in spaced relation with each other to prevent the sides of the body portion from bulging.

In testimony that I claim the foregoing as my own, I have hereto affixed my signature:

CHARLES H. BORST.
